UNITED STATES PATENT OFFICE.

ALFRED N. MARTIN, OF NEW DORP, NEW YORK.

RADIOPHONE AMPLIFIER.

Application filed April 21, 1923. Serial No. 633,649.

To all whom it may concern:

Be it known that I, ALFRED N. MARTIN, a citizen of the United States, residing at New Dorp, Staten Island, in the county of Richmond and State of New York, have invented certain new and useful Improvements in Radiophone Amplifiers, of which the following is a specification.

This invention relates to sound conducting and amplifying means of the receiving type pertinent to radio operations.

Having in mind numerous objections to the amplifying equipment or devices now commonly in use, such as tinny, nasal, and many other distinctly disturbing and distinctive kinds of sounds, not traceable or chargeable to the original broadcasting of musical or other sounds, in the development of this present equipment I contemplate a number of objects among which are the magnification or amplification of the transmitted sounds, whereby I obtain not only unusual volume but particularly pleasing effects, free or practically free from annoying or undesirable tonal effects; to provide an amplifying apparatus peculiarly constructed for the purpose of producing sweet or favorable tone qualities and which moreover are subject to very delicate or precise adjustment for the purpose desired; to provide a system or apparatus for amplification of sounds at the receiving station which includes means for magnifying the tones in a variable adjustable manner that is equivalent in this amplifying construction to a rheostat and socket for tuning a vacuum bulb in the now commonly used receiving set,—that is, it not alone magnifies the sound, but by the balance or adjustment of the sound magnifier or microphone, it can be made to do duty in modifying and increasing the volume or intensity in the amplifying system in a peculiarly novel manner, and also another object of my invention is to obtain by a new and peculiar combination of parts, a result heretofore unknown, with respect especially to the volume and quality of the tonal effect.

With the foregoing and other objects in view the invention consists in the arrangement and combination of parts hereinafter described and claimed, and while my invention is not restricted to the exact details of construction disclosed or suggested herein, still for the purpose of illustrating a practical embodiment thereof reference is had to the accompanying drawings, in which like

reference characters designate the same parts in the several views, and in which—

Figure 1 is a perspective view of a preferred embodiment of my invention. 60

Fig. 2 is a vertical longitudinal section of the same.

Fig. 3 is a diagram, indicating the arrangement of the elements within the resonant body somewhat as would be observed 65 with the top cover plate thereof removed and also indicating the circuit connections in series or parallel.

Fig. 4 is a detail view of one of my improved microphones or tone magnifiers. 70

Referring now more specifically to the drawings, but at the same time specifically asserting my intention not to be unnecessarily limited to the specific mechanism illustrated, I show a resonant body 10 which 75 may be thought of as being somewhat similar in size and construction to the body of a violincello but without a finger board or neck or other external attachments except possibly a handle 11 which may be employed in moving and manipulating the apparatus. This body 10 includes a top cover 12 connected removably by any suitable means to the rim portion 13 and having also a bottom plate 14. 80

The other main portion of the supporting or casing construction is a hollow base or sub-support 15, the same being indicated as of generally rectangular form and of rather shallow depth in proportion to its other dimensions. For convenience this base may be supported upon feet or legs 16 and 17, the latter being the shorter. The sub-support 15 except as now to be described is entirely closed and in itself constitutes a sound 95 amplifying medium. The top portion or cover plate 18 is provided with a central opening 19 suitably shaped to receive therein the downwardly convexed central portion of the bottom of the body 10 which is clearly 100 shown in Fig. 2. The length and breadth of the sub-support 15 may be less or greater than the corresponding parts of the body 10, and these two main parts are in practice secured or anchored together by any suitable 105 means, as for instance, the hooks 20 shown in Fig. 2. At any desired portions of the sub-support may be arranged sound vibration outlets each shown provided with a bell-like sounder or extremity. For this purpose I show three of such members connected at 110 and extending thence laterally sideways or

upward from openings 21 in the sides or ends of the sub-support, the sounders being indicated at 22. The apparatus may be stood or placed upon any convenient table, desk, 5 or the like, and at any desired distance from or relation to the usual or standard receiving set and to which my improvements are auxiliary.

With special reference now to Fig. 3, I 10 provide in connection with the resonant body or bodies above described, two batteries 23 and 23' both of which are preferably of the nature of the commonly used B batteries for receiving sets. Within the body 10 I place 15 a number of sound magnifiers or microphones of suitable construction and shown as four in number at 24, one adjacent to each end of the body and two others intermediate thereof, but all shown arranged in series or, 20 if desired, parallel, and in the circuit with the two batteries just described. Whether the coupling be in series or parallel will depend upon the nature or make up of the receiving set. Also arranged in the same circuit 25 are two loud speaking phones 25, one adjacent to each of the end microphones. The type of microphone best suited for this purpose is as shown in Fig. 4, the same comprising a carbon base plate 26 and a tiltable or 30 pivoted carbon stick 27. The stick is shown pivoted at 28 within a fork 29 of an insulated bracket 30 close adjacent to one side of the base plate 26. All the plates 26 are fixed rigidly to the bottom 14 of the body 35 10. One end of the stick 27 is provided with a series of fingers or teeth 31 having relatively sharp points, and the stick is so designed that these points will rest with more or less heft upon the plates 26. The firmness of this contact between the stick and the 40 plate is adapted to be varied or modified delicately or adjustably by means of a rider or weight 32 movable along the upper end of the stick and adapted to be fixed in adjusted 45 position by means of a set screw 33 or its equivalent. One connection of the circuit wire is made with the base plate 26 and the other with the stick, the latter connection being preferably through the pivot. It is 50 the adjustable balance microphone feature of this invention that is relied upon, in connection with the B battery connections and loud speaking phones 25, to produce the exceedingly well tuned and well purified character tones, suitable for filling any reasonable room or auditorium, according to the control at the adjustable receiving set. Of course there is no necessity nor intention of 55 employing head phones.

60 Located also preferably within the body 10 and in close relation to the two intermediate microphones I provide a number of other phones 34, preferably of the nature of loud speaking phones but which are 65 coupled, independently of the battery and

wiring above described, to the receiving set in a manner similar to the usual coupling of head pieces. The sounds received by and transmitted through the phones 25 and 34 pass through and are delivered from the 70 sounding bodies 10 and 15 with a remarkable sweetness and purity of quality as well as depth of volume.

Variations may be resorted to within the spirit and scope of my invention and parts 75 thereof used without others.

The microphone circuit is operated through the vibration of the adjustable microphones by the sounding body wherein they are contained, the vibrations of the sounding body being transmitted to the microphones through the carbon base 26 attached to said body. These vibrations cause the resistance at 31 to vary so as to render the current flowing through the phones 25 a pulsating one, in unison with signals received through the primal set, causing them to operate so as to add to the total volume of sound to be amplified within the sounding bodies 12 and 15.

90 I claim:

1. In a sound amplifying means, a body of violin form, a hollow resonant sub-support for said body which lies in direct contact therewith, a portion of the wall of one of which within the line of contact has been removed to allow the adjacent contacting wall to form a single partition and common sounding board within said line, allowing the more ready transmission of sound therethrough for the purpose of amplification, and means to initiate sound vibrations to be amplified thereby.

95 2. Mechanism as set forth in claim 1 in which the resonant body is hollow and is provided with a convex bottom, and the sub-support is provided with an opening into which said convex bottom is fitted.

100 3. Mechanism as set forth in claim 1 in which the sub-support is provided with a plurality of lateral openings.

110 4. In a sound amplifier as set forth, the combination of a hollow resonant body, a hollow resonant sub-supporting body therefor and to which the first mentioned body is secured in fixed position, a plurality of phones within one of the bodies operative from a radio receiving set to cause the vibration of the bodies, and microphone means within the body in an independent circuit 115 for the purpose of amplifying the sound emanating from the phones, said microphone means being operative by means of vibrations transmitted to the same at their points of attachment to the body.

120 125 5. The combination as set forth in claim 1 wherein the said means for initiating sound vibrations comprises a plurality of phones within one of the bodies operative from a receiving set to cause the vibration 130

of the bodies, and microphone means within the same body in an independent circuit for the purpose of amplifying the sound emanating from the phones, said microphone means being operative by means of vibrations transmitted to the same at their points of attachment to the body.

6. The combination as in claim 4 wherein the adjustable microphone consists of a

carbon base plate attached to said body, and a pivoted carbon stick one end of which makes contact with the carbon base plate, the electrical resistance of said contact varying with the vibrations transmitted to the microphone by the body.

In testimony whereof I affix my signature.

ALFRED N. MARTIN.
